UNITED STATES PATENT OFFICE.

WILLIAM HENRY KELLY, OF BRANDON, VERMONT, ASSIGNOR TO JOHN JENCKES, OF NAYATT POINT, RHODE ISLAND.

CIRCULAR-KNITTING MACHINE.

SPECIFICATION forming part of Letters Patent No. 414,863, dated November 12, 1889.

Application filed September 7, 1888. Serial No. 284,801. (No model.)

To all whom it may concern:

Be it known that I, WILLIAM HENRY KELLY, of Brandon, county of Rutland, State of Vermont, have invented an Improvement 5 in Circular-Knitting Machines, of which the following description, in connection with the accompanying drawings, is a specification, like letters on the drawings representing like parts.

10 This invention has for its object to improve and simplify knitting-machines of the class described in United States Patent No. 372,374, granted to me November 1, 1887. The machine described in the said patent is adapted 15 to automatically lift one needle after another at the ends of the series of needles which are employed in narrowing to make the first half of a heel or toe for a stocking, and to also automatically bring down one of said 20 needles after another from the ends of the said series of needles as the fabric or web is gradually widened to produce the complementary part of the heel or toe. In the said machine when widening was to be done the 25 operator had to fix the tumblers in place by set-screws and loosen the switch-plates from the holding action of screws, and when narrowing was to be done the operator had to reverse this operation—viz., had to fix each 30 switch-plate by a screw and loosen each tumbler from its holding-screw. The operation of controlling each tumbler and switch-plate independently of the others required considerable time.

35 The object of my present invention is to provide a more compact construction of parts and improved means for throwing the tumblers and switch-plates into and out of operation.

40 My invention consists, essentially, in a cam-cylinder, its drawing-down cams, tumblers adapted to automatically lift the needles singly, and pivoted switch-plates combined with longitudinally-movable slides carrying 45 the said switch-plates, and cam projections co-operating therewith to depress or turn the switch-plates automatically on or with relation to the said slides, as will be described; also a compound cylinder consisting, essentially, of an interior cylinder and a surrounding cylindrical jacket having an internal

groove and segmental slides, and segmental blocks movable in the said grooves and accessible from outside the said jacket combined with tumblers and with pivoted switch-plates and cams or projections co-operating therewith, substantially as will be described. 55

Other features of my invention will be described in the specification and in the claims at the end thereof. 60

Figure 1 is an inner side view laid out straight of a cam-cylinder and its attached parts embodying my invention. Fig. 2 is a top or plan view of the cam-cylinder. Fig. 3 is a partial section in the line x, Fig. 1. Fig. 4 is a partial section in the line x'. Fig. 5 is a detail showing the cams in a different position from that represented in Fig. 1. Fig. 6 is an outside elevation of the cylinder. Fig. 7 shows the segmental slide separately. Fig. 8 shows one of the switch-plates separately. Fig. 9 shows one of the blocks separately. Fig. 10 shows one of the tumblers, and Fig. 11 a needle such as used in my machine. 70

The cylinder herein shown is a compound 75 one, it being composed of a jacket, as C², within which is placed a cylinder C, having at its inner side a ledge or shoulder D, on which ride and rest the butts of the needles D', (see Fig. 11,) used for knitting when in their 80 regular position and not opposite the cams. The interior of the cylinder C is cut out to receive the usual lower cam-plates A B A², and above these cam-plates at opposite sides the plate B are pivoted in usual manner the 85 switch-cams E E². The cylinder C above the cam-portion B has secured to it the V-shaped or triangular plate J, the sole purpose of which is to act as a stop for the two tumblers K K², one of which is shown detached in Fig. 90 10, which tumblers of like shape are pivoted at opposite sides of and just below the center of the said plate J, as in Fig. 1, each tumbler having a projection, as 2, at its end.

The parts so far described, with the exception of the jacket C², are substantially the same as in my said patent, wherein like letters are used to designate like parts. Each tumbler has extended from it a pin, as 12, which is passed through a diagonal slot in the 100 cylinder portion C, the pin terminating in the groove 4 of the jacket C², so as to be acted

upon by a segmental block 13, free to slide in the said groove 4 between the two parts of the cylinder, a threaded stud, as 14, of the said block being extended through a slot, as *b*, cut 5 through the jacket, the said screw-stud receiving upon it a thumb-nut 15. The interior of the cylinder *C* has screwed or attached to it at each side of the said tumblers two cam projections, as *a a'*, forming upper cam-plates 10 which are considerably inclined, very much more so than the upper cam-plates represented in my said patent, the said projections *a a'* being set at a greater inclination to thereby enable the switch-plates *e e'*, employed to 15 pull the needles down singly when narrowing, to be located lower down in the machine and with their pivotal points more nearly in the line of the pivots of the tumblers *K K'*, thus gaining greater compactness of parts 20 and having easier operation of the needles. The projections *a a'*, referred to, at their under sides and at their ends next the said tumblers, are so shaped, substantially as shown in the drawings, as to permit the lips 25 2 of the tumblers to be placed just above the downturned points 3 of the said cam projections, when the tumblers are turned up out of operation and held against the projection *J*, as shown in Fig. 1, when ordinary knitting 30 and widening is being done.

The jacket *C*² is provided at its inner wall with an annular groove 4, and the inner cylinder *C*, containing the usual cams and toothed ring *C*⁴, is secured to it by screws 5 35 or otherwise, the said groove being cut entirely through the exterior of the jacket at four points, there being two slots, as *b*, and two, as *b'*, at each side of the projection *J*, the drawings showing but two of the said slots, 40 as they are just alike. The groove 4, referred to, at each side the projection *J* and beyond the blocks 13, serves to receive in it like segmental slides *f*, having hollow hubs (see section, Fig 3) which extend through the 45 like slots *b'*, the said hubs receiving loosely the studs 6 of the like switch-plates *e e'*, the said studs outside the jacket having each applied to them a thumb-nut, as 16, which is used to hold in place or confine to the said 50 studs the free end of a spring, as *e*², extended through a hole in the shank of the stud 6, (see Fig. 6,) the other end of the said spring being fixed by a suitable screw, as 8, to the jacket *C*², the normal tendency of the spring *e*² being to 55 not only keep the pin 10 projected from one side of the switch-plate (see Fig. 8) pressed up against the under side of the cam projection or plate *h h'* above it, but also to keep the segmental slide carrying the switch 60 pressed toward the knitting-point or toward the tumblers. As herein shown, the outer threaded end of each stud 6 is split. The cylinder *C* at its inner side has two like pushing-down cams, as *g g'*, each located just back of one of the said switches, as fully shown in 65 Fig. 1.

When tubular knitting is being done, all

the needles are down and the tumblers *K K'*² are held up next the triangular block *J* by the action against the pins 12 of the said 70 tumblers of one end of the segmental blocks 13, referred to, the block at such times being fixed in position. When a heel or toe is to be knitted, those needles which are not to be employed in the production of the heel are raised 75 by hand in usual manner, all the needles which are to be used in the widest course of the heel being left down. In this condition the segmental blocks 13 are loosened and moved in the groove 4 toward the segmental 80 slides *f*, carrying the switch-plates *e e'*, and the said blocks are made to act against the said slides and push them and the switch-plates back until the said switch-plates, by the action of the pins 10 against the under 85 sides of the projections *h* or *h'*, are lowered sufficiently to pass under the butts of the raised needles, and in this condition the said blocks are fastened by the thumb-nuts 15. The cylinder being now reciprocated in usual 90 manner from right to left, the butts 20 of the endmost needles of the series of needles left down for narrowing arrive one after the other in successive reciprocations of the cam-cylinder against the tumblers *K* or *K'*, according 95 to the direction of movement of the cylinder, and, meeting the said tumblers above their lips 2, are pushed against by the said tumblers in such manner that the tumblers are turned upon their pivots, and in so doing 100 each tumbler acts to lift with it the needle, the butt of which bears against the tumbler, thus lifting the said needles one at a time up out of the range of the knitting-cams, leaving the said needles lifted until they are again to 105 be lowered automatically in widening, as will be described, by the switch-plates *e e'*. The tumbler lifted by the first needle of the series of needles employed in the heel or toe remains up, while the butts of all the needles being 110 used for narrowing pass under them, one needle at a time being lifted, as described, from the leading end of the series of needles during each reciprocation of the cam-cylinder until the narrowest course for the heel or toe 115 has been knitted, immediately after which and preparatory to widening to produce the second half of a heel or toe the segmental blocks 13 are again loosened and moved to place the tumblers described against the block 120 *J*, permitting the segmental slides *f* to approach the tumblers far enough to enable the points of the switch-plates to extend up far enough to engage the butts of those needles which have been elevated, as described, in 125 narrowing, the point of one of the said switch-plates striking in succession the butt of the leading needle in the direction of the rotation of the cylinder of the series of needles elevated, as described. During the operation 130 of widening the segmental slides carrying the switch-plates are free to be slid in the groove 4 away from the tumbler next to it and against the action of the spring *e*². The

butt of the leading needle of the series of elevated needles at each reciprocation of the cam-cylinder strikes the upturned end of a switch-plate, and the switch-plate is thereby temporarily arrested, so that in the further movement of the cylinder the segmental slide is made to travel back in the groove 4 opposite the direction of rotation of the cylinder, such movement by the action of the projection of the switch-plate against the cam-plate or projection h h' above it causing the front end of the switch-plate in engagement with the butt of the endmost needle to turn down, taking with it the said needle, so that the butt of the latter needle passes under the switch-plate and under the drawing-down cam g or g' behind it, the butts of all the elevated needles except the one so engaged by the switch-plate passing above the switch-plate and the drawing-down cam g or g' behind it. The projections h h' do not lie immediately above the switch-plates or in the same vertical plane, so the said projections do not act against the butts of and pull down the needles. As described, the elevated needles used in narrowing are gradually brought down for widening, and the widest course of the heel or toe having been completed after the commencement of the widening all the needles previously thrown up out of operation and not used in narrowing and widening are thrown down in any usual manner. The switch-cams E E^2 act in connection with the needles in the usual manner for knitting.

35 I claim—

1. The cam-cylinder, the cams g g' , and the pivoted switch-plates and their co-operating springs, combined with the longitudinally-movable slides carrying the said switch-plates and cam projections co-operating therewith to depress or turn the switch-plates automatically on or with relation to the said slides, substantially as described.

2. The compound cylinder consisting, essentially, of the cylinder C and the jacket C^2 slotted at b b' , and having an internal groove 4, the cams E E^2 , and the segmental slides and segmental blocks placed in the said grooves, and having shanks or projections accessible for their movement in the said groove from outside the said jacket combined with the tumblers, the pivoted switch-plates, springs to actuate them, cams g and g' , and cams or projections, as h h' , to operate substantially as described.

3. The cylinder portion C , the jacket C^2 , having the groove 4, the segmental slides f , placed in the said groove, the pivoted switch-plates mounted on the said segmental slides, the springs to normally elevate the points of the switch-plates and to hold the slides pressed toward the knitting-cams, and the segmental blocks 13, placed in the said groove, combined with the cam-plates A B A^2 , the cams E E^2 and tumblers, and cam projections a a' , the said segmental blocks when moved to permit the tumblers to drop for widening also pushing back the segmental slides to depress the points of the switch-plates and the projections h h' , substantially as described.

In testimony whereof I have signed my name to this specification in the presence of two subscribing witnesses.

WILLIAM HENRY KELLY.
